UNITED STATES PATENT OFFICE.

WILLIAM GIBSON, OF DANBURY, CONNECTICUT, ASSIGNOR TO THE GIBSON MFG. CO., OF DANBURY, CONNECTICUT, A CORPORATION.

TELEPHONE-MOUTHPIECE.

No. 913,947.

Specification of Letters Patent.

Patented March 2, 1909.

Application filed April 20, 1908. Serial No. 428,228.

To all whom it may concern:

Be it known that I, WILLIAM GIBSON, a citizen of the United States, residing at Danbury, in the county of Fairfield and State of Connecticut, have invented a new and useful Improvement in Telephone-Mouthpieces; and I do hereby declare the following, when taken in connection with the accompanying drawings and the numerals of reference 10 marked thereon, to be a full, clear, and exact description of the same, and which said drawings constitute part of this specification, and represent, in—

Figure 1 a sectional view of a mouth-piece 15 constructed in accordance with my invention, showing the metal shell in side elevation. Fig. 2 a sectional view of the shell, detached. Fig. 3 a plan view of the shell.

This invention relates to an improvement 20 in telephone mouth-pieces.

The advantages of the use of glass in telephone parts is too well recognized to need setting forth here, but as a mouth-piece, glass has not only the advantages of being 25 a perfect non-conductor, but can without difficulty be readily cleansed without injuring the surface of the material from which it is formed. A further advantage of forming the mouth-piece from glass or vitreous material is that it may be readily enameled or 30 otherwise colored to correspond with the furnishings of the room in which it is placed; but difficulty is found in forming a glass mouth-piece with threads by which it may 35 be engaged with the telephone, and the object of this invention is to form the mouth-piece from glass or vitreous material and mount a metal cup or shell at the inner end thereof by which it may be connected with a 40 telephone; and the invention consists in the construction hereinafter described and pointed out in the claim.

In carrying out my invention I form the mouth-piece 2 which is of usual shape, from

glass or vitreous material and by the term 45 "glass" as hereinafter used, I wish to be understood as including any equivalent vitreous material. To provide means for securing the mouth-piece in place I form the cup or shell 3 from metal with external threads 4 50 corresponding to the threads usually formed at the inner end of the mouth-piece. These threads 4 form a shoulder 5 which is seated against the inner edge of the mouth-piece into which the cup projects, the bottom of 55 the cup having perforations 6 as usual in telephone mouth-pieces. The inner walls of this mouth-piece are slightly tapered, and when the shell 3 is inserted into the inner end the bottom of the cup or shell is expanded 60 within the mouth-piece so as to interlock it therewith, or to prevent its withdrawal, the shoulders forming a stop to limit the inward movement of the shell.

In forming this mouth-piece from glass or 65 other vitreous material they are not perfectly round, and expanding the shell within the mouth-piece the shell conforms to the irregularities of the surface of the mouth-piece and is therefore interlocked therewith against 70 rotation. The shell is therefore firmly and permanently interlocked with the mouth-piece.

I claim:—

A telephone mouth-piece formed from 75 glass, combined with a cup-like shell inserted into the inner end thereof, said shell formed with external threads and the inner end of the shell expanded within the mouth-piece, substantially as described.

In testimony whereof, I have signed this specification in the presence of two subscribing witnesses.

WILLIAM GIBSON.
